DESIGN FOR AN EMBROIDERED TEXTILE FABRIC OR SIMILAR ARTICLE

Max Hofmann, New York, N. Y.

Application October 30, 1933. Serial No. 49,591

Term of patent 3½ years

To all whom it may concern:

Be it known that I, MAX HOFMANN, a citizen of the United States, residing at 147 West 66th Street, Borough of Manhattan, city, county and State of New York, have invented a new, original, and ornamental Design for an Embroidered Textile Fabric or Similar Article, of which the following is a specification, reference being had to the accompanying drawing, forming part thereof.

The single figure in the drawing shows a plan view of a portion of the embroidered textile fabric of my new design.

I claim:

The ornamental design for an embroidered textile fabric or similar article substantially as shown.

MAX HOFMANN.
